COTTON GINNING APPARATUS

John Blewett, Dallas, Tex., assignor to The Murray Company, Dallas, Tex., a corporation of Texas

Application March 14, 1938, Serial No. 195,730

9 Claims. (Cl. 19—59)

This invention relates to new and useful improvements in cotton ginning apparatus.

One object of the invention is to provide an improved apparatus particularly adaptable to air blast cotton gins, whereby separation of the motes, trash, and other extraneous material, from the cotton is facilitated and the ginning efficiency is increased.

An important object of the invention is to provide an improved air nozzle for cotton gins which is so constructed that the moting area of the saws is increased and accumulation of "green" or "wormy" cotton on the nozzle, which accumulation interferes with the operation of the gin, is eliminated, whereby the ginning operation is facilitated.

A particular object of the invention is to provide an improved cotton ginning apparatus, wherein an arcuate shield or plate is disposed contiguous to the ginning saws and adjacent the air nozzle, said shield being readily adjustable whereby more or less peripheral area of the ginning saws may be exposed to increase or decrease the moting area in accordance with the condition of the cotton; the shield also including an extension which overlies the air nozzle and prevents a suction being created in the moting chamber by the air emitting from the nozzle.

Another object of the invention is to provide an improved air inlet for cotton gins which inlet may be readily varied in size so as to control the suction created adjacent the inlet, whereby the inlet may be adjusted in accordance with the condition of the cotton to increase mote separation and thereby increase ginning efficiency.

A further object of the invention is to provide an improved air inlet located between the air conduit and the lint flue, said inlet being formed by a stationary member and a movable member, the latter being movable toward and away from the stationary member in an arcuate path concentric to the ginning saws, whereby the relative positions of the members to the saws never vary regardless of the positions of said members with relation to each other.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a partial side elevation of a gin, hav-

ing the improved air nozzle, constructed in accordance with the invention, applied thereto.

Figure 2 is an enlarged transverse, vertical, sectional view taken through the air nozzle and showing the upper end of the lint duct,

Figure 3 is a view similar to Figure 2 and showing the lint duct moved to another position,

Figure 4 is a partial transverse, vertical, sectional view taken on the line 4—4 of Figure 2,

Figure 5 is an enlarged elevation of the actuating arm for the duct adjusting means,

Figure 6 is an enlarged, vertical, sectional view, showing the means for varying the moting area of the saws,

Figure 7 is a view similar to Figure 6, with said means moved to another position,

Figure 8 is a partial end view of one of the supporting castings for the mechanism, and

Figure 9 is a transverse, vertical, sectional view of the usual type of air discharge nozzle.

In the drawings, the numeral 10 designates an air blast cotton gin of the usual construction. The gin includes the roll box 11, ginning saws 12 and ribs 13 which are located and mounted in the conventional manner. Behind the saws 12, a moting chamber 14 is provided and a conveyor 15 is disposed in the lower end of said chamber. An air supply conduit (not shown) which is located at the rear of the gin communicates with an upwardly curved air supply duct 17 which terminates adjacent the ginning saws. A downwardly curved lint duct 18 extends from the saws contiguous to the supply duct 17 and conducts the lint from the saws.

The gin operates in the usual manner with the 35 saws 12 pulling the cotton between the ribs 13. The motes, pin trash and other fine extraneous matter is carried through the ribs by the saws and by the lint engaging on the saw teeth. Centrifugal force is depended upon to throw the motes, 40 and other foreign particles, from the saws into the mote chamber 14 and the separated motes fall onto the conveyor 15 and are conveyed from the gin. The air supplied from the air duct 17 is directed against the saws by an air nozzle A at the 45 upper end of this duct and the air stream removes the cotton from said saws. The air stream then passes downwardly through the lint duct 18, carrying the lint therewith. The above is the conventional method for ginning cotton and has 50 been described merely for the sake of clarity.

The invention resides in the nozzle A and in a mote shield B above said nozzle, as well as in the construction of the upper end of the lint duct 18. As clearly shown in Figure 2, the rear wall 17a 55

of the air supply duct 17, which extends throughout the transverse width of the gin, is curved rearwardly at its upper end. An angular deflecting member 20, having a substantially inverted V-shape, has its lower longitudinal edge portion secured to the upper edge portion of the duct 17 and said member extends throughout the length of the duct. The member has its outer or rear side 20a inclined forwardly from its lower end and has its other side 20b bent downwardly contiguous to the saws 12. This inner side 20b is arcuate being concentric to the peripheries of the saws, whereby it is spaced from said saws an equal distance throughout its width.

Coacting with the curved side 20b of the angular deflecting member 20 to form an air outlet for the duct 17, is a second deflecting member 21. This member has its lower longitudinal edge portion secured to the upper end of the outer wall 17b of the duct 17. The upper end of the member 21 is bent inwardly so as to extend into the duct and a transverse rod or bar 22 supports this upper end. The bar has each end supported in an opening 22' formed in an end casting C which is fastened to the inner side of each end wall of the gin frame.

With this arrangement, the air traveling upwardly through the duct 17 strikes the overhanging upper portion of the deflecting member 21 and is directed against the inclined side 20a of the angular member 20. The air stream is then turned downwardly due to the shape of the member 20 and escapes through the space between the member 21 and the lower edge of the curved side 20b of the member 20. The inclination of the upper portion of the member 21 is such that the escaping air stream is directed substantially tangentially of the saws, whereby the cotton lint engaging on the saw teeth is stripped off of said teeth. This lint, as well as the air stream is drawn into the lint duct 18, from where it is conducted to the usual baling apparatus (not shown).

It has been the general practice to form the deflecting member 20' of a rounded contour in cross-section, as shown in Figure 9, instead of angular as herein described. Such rounded wall is undesirable as it presents a surface which is exposed to the motes being thrown off by the rotating saws, and accumulation of extraneous matter on the member 20' occurs. This accumulation takes the form of a gummy substance and is particularly obvious when ginning green cotton or wormy cotton. The accumulation is most undesirable and often necessitates halting of the gin to permit the nozzle to be cleaned, as too great an accumulation interferes with the gin operation. By constructing the top of the nozzle A of the angular member 20, a sharp corner is presented and the extraneous matter being thrown off by the saws has substantially no surface on which to accumulate and, therefore, such accumulation is practically eliminated.

Another feature of the angular member 20 is the reduction of the induced flow from the moting chamber 14 into the lint duct. This induced flow of air is created by the suction formed by the air emitting from the nozzle A. By making the member 20 angular the air and motes within the mote chamber behind the member are not drawn into the lint duct as it is difficult to draw the same around the sharp corner formed at the top of said member. If the member is of a rounded contour, the air easily follows the rounded surface and therefore, the motes and

other extraneous matter, are pulled into the lint duct. With the angular member, induced flow at the nozzle is substantially eliminated.

Although the shape of the nozzle A tends to reduce the accumulation on its surface, and to cut down the induced flow, it will not entirely eliminate the same. In order to completely obviate any possible accumulation, as well as to control the moting area of the saws, an arcuate shield or plate 24 is disposed contiguous to the saws 12. The plate extends entirely across the interior of the gin and has its lower end engaging and riding on the surface 20b of the nozzle. The plate is curved on an arc concentric to the periphery of the saws and is bent upon itself to form a rearwardly inclined skirt or extension 25, which overlies the nozzle A and projects downwardly into the mote chamber, as is clearly shown in Figure 6. The ends of the extension are bent upwardly to form flanges 26 which add rigidity to the skirt. The plate and extension are supported by links 27 which are located one at each end of the extension adjacent the castings C. The lower end of each link is pivoted to one of the flanges at the upper end of said flange, while the upper end of the link is pivotally fastened to the outer end of an actuating arm 28. The arms 28 are fastened on an adjusting shaft 29 which has its ends journaled in the end of the frame. One end of the shaft projects through the frame and has an operating handle 30 secured thereto. The handle is movable to various positions with relation to an indicator segment 31 which is mounted on the exterior of the gin frame.

When the handle 30 is swung, the shaft 29 is rotated and the arms 28 are swung, whereby the links 27 move the plate 24 and extension 25 vertically within the moting chamber with relation to the nozzle A. The plate and extension are guided in their movement by a horizontal rod 32 which is fastened to the inner surfaces of said plate and skirt, the extremities of said shaft being movable in guide slots 32' formed in the castings C.

When the plate 24 is in the position shown in Figure 6, the upper end of said plate is lowered whereby increased saw surface is exposed within the moting chamber. This position of the plate increases the moting area as the motes may be thrown off the saws at a further point in rotation. The motes which are thrown off fall onto the skirt or extension 25 and due to its inclination are conducted to the conveyor 15. The skirt or extension not only forms a chute for the separated motes but since it overhangs the nozzle A, it prevents the creation of a suction in the mote chamber above the nozzle, such suction normally being due to the ejection of air from the nozzle against the saws. This suction is further defeated by the lower end of the plate or shield 24 engaging the inner side 20b of the nozzle.

When it is desired to reduce the moting area of the saws, the handle 30 is swung to rotate the shaft 29 so as to move the plate 24 and extension 25 upwardly, as shown in Figure 7. This causes the plate to move upwardly with relation to the saws so as to cover more area thereof and thereby expose less saw area to the moting chamber. Thus, the plate may be suitably adjusted to suit the condition of the cotton and in all adjusted positions, a creation of suction in the mote chamber is defeated. In ginning wormy or green cotton, an accumulation might occur on the plate but this accumulation will be automatically removed

by the rotating saws and by the suction created by the air emitting from the nozzle A.

The amount of air passing into and through the lint duct 18 must be varied in accordance with the condition of the cotton being ginned. To provide a simple method of adjusting the inlet opening of the lint duct 18, the forward wall 18a of said duct is movable with relation to the rear wall thereof. This forward wall curves downwardly and is suitably secured at its lower end, whereby the entire wall may be moved inwardly and outwardly of the rear wall thereof.

The upper end of the wall 18a is bent upon itself to form an extension 33 and a transverse rod 34 is confined between the extension and the upper end of the wall. This rod is welded, or otherwise secured, to the rod and wall. The ends of the shaft project into guide slots 35 which are formed in the castings C. These slots are arcuate and are concentric to the peripheries of the saws 11. When the front wall 18a of the duct 18 is moved with relation to the other wall thereof, the rod 34 moves within the guide slots to guide the movement of said wall, whereby the upper end 25 of the wall is maintained in fixed relation to the saws during its movement. Thus, when the wall 18a is moved, the inlet of the duct 18 is varied to increase or decrease the size thereof.

For readily swinging the wall 18a, an outwardly projecting ear 36 is provided at each end of the wall 18a, being located below the rod 34. A link 37 is pivotally secured to each ear and has its lower end pivoted to the outer end of an arm 38. The inner end of each arm is fastened on a transverse shaft 39 and the ends of the shaft project through the end walls of the gin frame 10, being journaled in suitable bearings secured to said end walls. When the shaft 39 is rotated, the arms 38 are swung whereby the links are 40 moved to move the wall 18a.

For rotating the shaft 39, an arm 40 is secured to one end of the shaft and the arm is located exteriorly of the gin. The arm has a collar 41 on its outer end and said collar is movable along a pin 42, which has its upper end pivoted on a bolt 43 threaded into the end wall of the gin 10. As the collar 41 is moved longitudinally of the pin, the shaft 39 is rotated to swing the front wall 18a of the duct 18. The pin 42 is threaded throughout its length and lock nuts 44 are threaded thereon. The collar 41 of the actuating arm is confined between said nuts and after said arm has been swung to a position to obtain the proper adjustment of the duct inlet, the nuts are 55 tightened against said collar to maintain the adjustment.

What I claim and desire to secure by Letters Patent is:

1. The combination with an air blast cotton gin having an air supply duct terminating adjacent the ginning saws, of an air nozzle including, an angular deflecting member secured to the upper end of the duct and arranged to direct the air onto the saws to strip the cotton lint from the teeth thereof, an arcuate shield adjacent the inner wall of the nozzle and extending contiguous to the periphery of the saws for controlling the moting area of the saws and for defeating an induced flow of air around the top of the nozzle, 60 said shield being movable in a path substantially concentric to the periphery of the saws and an inclined extension integral with and depending from the shield and overhanging the nozzle for guiding the motes from the saws and for preventing induced flow of air around the nozzle.

2. The combination with an air blast cotton gin having an air supply duct terminating adjacent the ginning saws, of an air nozzle including, a deflecting member secured to the upper end of the duct and arranged to direct the air onto the saws to strip the cotton lint from the teeth thereof, an arcuate shield having its lower portion engaging the inner wall of the nozzle so as to provide a continuation thereof and extending contiguous to the periphery of the saws for controlling the moting area of the saws and for defeating an induced flow of air around the top of the nozzle, and means for moving the shield with relation to the saws to uncover more or less of the peripheral area of the saws exposed to the moting chamber 15 of the gin.

3. The combination with an air blast cotton gin having an air supply duct terminating adjacent the gin saws, of an air nozzle having its upper end substantially triangular in cross section, and an elongate arcuate shield adjacent the teeth of the saws for controlling the moting area and having its lower portion movably supported upon the inner triangular wall of the nozzle.

4. The combination with an air blast cotton gin having an air supply duct terminating adjacent the gin saws, of an air nozzle having its upper end substantially triangular in cross section, an arcuate shield adjacent the teeth of the saws for controlling the moting area and having its lower portion 25 movably supported upon the inner triangular wall of the nozzle, and a skirt integral with and extending rearwardly from the shield and overhanging the outer triangular wall of the nozzle.

5. The combination with an air blast cotton gin having an air supply duct terminating adjacent the gin saws, of an air nozzle having its upper end substantially triangular in cross section, an arcuate shield adjacent the teeth of the saws for controlling the moting area and having its lower portion movably supported upon the inner triangular wall of the nozzle, and means having an actuating element located exteriorly of the cotton gin for arcuately adjusting said 45 shield.

6. The combination with an air blast cotton gin having an air supply duct terminating adjacent the gin saws, of an air nozzle having its upper end substantially triangular in cross section, a movable arcuate shield adjacent the teeth of the saws for controlling the moting area and having its lower portion engaging the inner triangular wall of the nozzle, a skirt integral with and extending rearwardly from the shield 50 and overhanging the other triangular face of the nozzle, and means having an actuating element located exteriorly of the cotton gin for arcuately adjusting said shield and extension as a unit.

7. The combination with an air blast cotton 60 gin having an air supply duct terminating adjacent the ginning saws, of an air nozzle having its upper end substantially triangular in cross section, a movable shield substantially triangular in cross section receiving the upper end of 65 the nozzle therein and having one face adjacent the teeth of the saws for controlling the moting area of the saws, and means operable from the exterior of the gin for adjusting the shield upwardly with relation to the upper end of the 70 nozzle and maintaining the shield and the nozzle in overlapping relation.

8. The combination with an air blast cotton gin having an air supply duct terminating adjacent the teeth of the saws, of an air nozzle 75

including, an angular deflecting member secured to the upper end of the duct and arranged to direct the air onto the saws to strip the cotton lint from the teeth thereof, a shield overhanging said member and movable up and down thereon, said shield having its front side contiguous to the saws for controlling the moting area thereof and for defeating an induced flow of air around the top of the nozzle, and means operable from the exterior of the gin stand for adjusting said shield to move it up or down for controlling the moting area of the saws.

9. The combination with an air blast cotton gin having an air supply duct terminating adjacent to ginning saws, of an air nozzle includ-

ing, an angular deflecting member secured to the upper end of the duct and arranged to direct air onto the saws to strip the cotton lint from the teeth thereof, an arcuate movable shield having its lower portion overlying and engaging the inner wall of the nozzle so as to form a continuation thereof and extending contiguous to the periphery of the saws for controlling the moting area of the saws and for defeating an induced flow of air around the top of the nozzle, and means for moving the shield concentrically with relation to the saws to uncover more or less of the peripheral area of the saws exposed to the moting chamber of the gin.

JOHN BLEWETT. 15
